(57) **CLAIM**

The ornamental design for an ice chest tray, as shown and described.

DESCRIPTION

FIG. 1 is a front perspective view of an ice chest tray of the present invention.

FIG. 2 is an overhead view of an ice chest tray depicted in FIG. 1.

FIG. 3 is a bottom view of an ice chest tray depicted in FIGS. 1 through 2.

FIG. 4 is a front view of an ice chest tray depicted in FIGS. 1 through 3.

FIG. 5 is a rear view of an ice chest tray depicted in FIGS. 1 through 4.

FIG. 6 is a side view of an ice chest tray depicted in FIGS. 1 through 5; and,

FIG. 7 is an alternate side view of an ice chest tray depicted in FIGS. 1 through 6, rotated about a substantially horizontal axis from the view depicted in FIG. 6.

The present invention is an ice chest tray insert for use in food storage including, without limitation, keeping meat or other food items dry from ice water melt and maintaining food freshness within a conventional ice chest.
